ATTORNEY

UNITED STATES PATENT OFFICE.

CHARLES BOSWORTH, OF BROOKLYN, NEW YORK.

DESIGN FOR A PICTURE-FRAME MOLDING.

SPECIFICATION forming part of Design No. 25,216, dated March 3, 1896.

Application filed January 31, 1896. Serial No. 577,627. Term of patent 3½ years.

To all whom it may concern:

Be it known that I, CHARLES BOSWORTH, a citizen of the United States, residing at Brooklyn, in the county of Kings and State of New York, have invented and produced a new and original Design for Picture-Frame Moldings and the Like, of which the following is a specification, reference being had to the accompanying drawing, forming part thereof.

10 The essential features of my design consist in the configuration of the frame and its ornamentation, as shown in the accompanying drawing.

15 My design is suitable for picture, mirror, and other frames.

At A are the large leafy ornaments, with the shell or leafy ornaments B placed therein, between which are the large leaves C and small leaves c extending to the ornaments

20 A on each side, all of which are raised in relief.

The exterior surface of the molding is ornamented with the foliated figures, as shown

at a. The base is ornamented, as shown at D, in imitation of stipple-work.

25

The ornamentation at the corner of the molding is composed of leaves or parts of leaves, producing a leafy representation E, which projects upwardly and inwardly toward the center of the molding, all of which are raised in relief, at the base of which is a foliated figure d.

20 The outer surface of the molding is ornamented with a line of foliated figures e.

What I claim, and desire to secure by Letters Patent, is—

The design for a picture-frame molding, and the like, substantially as herein shown and described.

Signed at the city of Brooklyn, county of Kings, and State of New York, this 24th day of January, 1896.

CHARLES BOSWORTH.
